(57) **CLAIM**

What is claimed is the ornamental design for a protective case for a mobile device, as shown and described.

DESCRIPTION

FIG. 1 is a rear perspective view of a protective case for a mobile device showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a sectional view taken along line 8-8 in FIG. 2;

FIG. 9 is a sectional view taken along line 9-9 in FIG. 2; and, FIG. 10 is a rear perspective view of the protective case for a mobile device of FIG. 1, shown in an alternate position of use.

Broken lines showing a strap illustrate environmental subject matter that forms no part of the claimed design.

1 Claim, 9 Drawing Sheets
